US0D1040184S

(12) United States Design Patent (10) Patent No.: US D1,040,184 S
(45) Date of Patent:  Aug. 27, 2024

(54) PORTION OF A DISPLAY SCREEN WITH ICON

(71) Applicants: SINTAI OPTICAL (SHENZHEN) CO., LTD., Shenzhen (CN); ASIA OPTICAL CO., INC., Taichung (TW)

(72) Inventors: Yu-Han Wang, Taichung (TW); Yu-Chang Wung, Taichung (TW); Wei-Ning Huang, Taichung (TW)

(73) Assignees: SINTAI OPTICAL (SHENZHEN) CO., LTD., Shenzhen (CN); ASIA OPTICAL CO., INC., Taichung (TW)

() Term: 15 Years

(21) Appl. No.: 29/837,974

(22) Filed: May 10, 2022

CLAIM

The ornamental design for a portion of a display screen with an icon, as shown and described.

DESCRIPTION

The broken lines in the FIGURE show a display screen or portion thereof, and form no part of the claimed design.

The attached Appendix includes a reference view relating to the present design, and forms no part of the claimed design.

1 Claim, 1 Drawing Sheet
